UNITED STATES PATENT OFFICE.

JOHN H. SHECKLER, OF CHICAGO, ILLINOIS, ASSIGNOR TO UNDERWOOD TYPEWRITER COMPANY, OF NEW YORK, N. Y., A CORPORATION OF DELAWARE.

TYPE-WRITING MACHINE.

1,203,657.

Specification of Letters Patent. Patented Nov. 7, 1916.

Application filed February 19, 1914. Serial No. 819,637.

To all whom it may concern:

Be it known that I, JOHN H. SHECKLER, a citizen of the United States, residing in Chicago, in the county of Cook, and State of Illinois, have invented certain new and useful Improvements in Type-Writing Machines, of which the following is a specification.

This invention relates to devices to be employed in conjunction with typewriting machines, for feeding loose sheets, such as envelopes, telegraph blanks, and the like, automatically from a magazine, to and across the impression zone on a platen, by the application of the usual means for rotating such platen.

With these and other objects in view, the invention consists of a magazine, with associated feeding and driving devices, the whole contained in one structure adapted to be quickly and easily placed in position upon a typewriting machine securely and operatively supported thereon, and removed therefrom with equal facility. The magazine may contain a large number of loose sheets, which are spring pressed therein toward feed rollers, which latter are adapted, in their rotation, to pick off in a sliding action, the forward sheet with which they are in contact, and to deliver said sheet downwardly over the forward downwardly-inclined lip or edge of the magazine floor; it being found by me that under this system of delivery, the rollers having highly sensitive and efficient friction surfaces, the sheets behind the one being removed, are not disturbed at the time of such removal.

The invention further includes the various adjustment and guard devices, as well as the novel drive mechanism, all as will be particularly described in the specification and pointed out in the claims.

Other features and advantages will hereinafter appear.

In the accompanying drawings, Figure 1 is a front perspective view of my improved magazine and feed device for loose sheets as operatively mounted on the carriage of a typewriting machine. Fig. 2 is a rear, perspective view of said device. Fig. 3 is a vertical section taken on the line 3—3 of Fig. 2, but showing the front bail as swung to render the feed inoperative. Fig. 4 is a vertical section taken on the line 4—4 of Fig. 1.

The invention is shown as applied to a typewriting machine of the usual Underwood type, wherein a platen 1 is mounted on a shaft 2, journaled in bearings on a platen frame 3, which is moved along the printing point of the type 4, by a carriage 5, the platen frame being included in, or forming part of, said carriage. At the end of each line of writing, the carriage 5 is returned to the starting point by means of a lever 6, mounted on the said carriage, which lever is also adapted to rotate or line-space the platen, by driving back a plunger or slide 7, thereby operating a pawl 8 carried by said slide, to feed a ratchet or line-space wheel 9 that is fast on the platen shaft 2.

The paper or work-sheets 10 are supported in a rearwardly-inclined vertical stack in a magazine composed of a rear frame wall 11, side wings or walls 12, and a base 13, which base, while being slightly uptilted in its forward extension from rear wall 11 to form a normally retaining support for the sheets 10 placed edgewise thereon, is provided, toward its forward edge, with a downward inclination on lips 13^a, to slightly advance the lower edge of the forward sheet, and to enable said forward sheet to be slipped thereover in the feeding operation to be described hereinafter. The said stack of sheets 10 is impelled forwardly toward frictional feed rolls 14, mounted on a shaft 15 that is journaled in bearings therefor in the side wings 12, by means of an auxiliary rear frame 16, lying between the wall 11 and the rear surface of said stack of sheets, said frame 16 having upwardly-extending arms 16^a, terminating in bent fingers 16^b, entered in slots 11^a in the frame 11, to effect a hinge-like removable connection. Secured to said frame 11 are a number of springs 17, two of these springs being shown in the drawings, said springs extending downwardly from their points of connection to a point near the lower end of the auxiliary frame 16, where they exert outward pressure against said frame 16, thereby causing said frame to force the stack of sheets against the feed rolls 14 with the requisite degree of pressure.

The loose sheets of the stack contained in the magazine aforesaid, are held from falling forwardly out of said magazine, by means of a vertical arm 18 arranged at the back of frame 11, and having vertically slid-

ing movement on said frame through lugs 18^a on said arm engaging in a vertical slot 11^b in frame 11. Said arm 18 extends upwardly to an adjusted position, where its 5 forwardly and downwardly bent finger 18^b will be in front of the upper margins of the sheets in the magazine, and said arm is retained or set in that adjusted position by means of a wing-screw 11^c, threaded into 10 frame 11, through a vertical slot 18^c in said arm.

The sheets 10 are fed downwardly toward the platen by the rolls 14, of which two are 15 shown in the drawings, each being provided with frictional surfaces. Of course, the particular number of feed rolls is unimportant, excepting with regard to the uniformity of the frictional drag they apply to the sheets, and for this purpose, they may 20 be employed in suitable number and location. To enhance their serviceability, the rolls 14 are provided with a peripheral surfacing of frictional material, and in the example shown, I have indicated at 14^a, a 25 number of corrugated bands as placed about said rolls, said bands 14^a being in frictional contact with the forward surface of the front sheet 10 in the magazine.

Under the frictional arrangement referred to the rotation of the rolls 14, clockwise in Fig. 4, will cause the forward sheet 10 to be fed downwardly from the stack, passing, as shown in Fig. 4, between the down-turned lip 13^a of the base 13 and said 30 rolls, and being guided thence to the platen and its feed rolls 28, by forwardly-depend- 35 ing guide fingers 19, which extend from a front bar 19^a connecting the wings 12, and by the usual paper shelf or table 20, upon 40 which latter the magazine may be mounted. In the example shown, where the table 20 has the upper beaded or hooked edge 21, the lower rear edge of the frame 11 may have 45 hook-like lugs 11^a, to straddle said beaded edge and thus effect a locking engagement with said table.

The magazine is otherwise removably connected to the typewriting machine by a 50 rod 22, passed through a support or lateral extension 12^a of one of the side wings 12 of the magazine frame, said extension 12^a being supported in a lower plane than base 13 by a connecting web 12^b. Said rod 22 has a hook 22^a at its lower end for engage- 55 ment with a rod 23 or other member on the platen frame. The rod 22, above ex- 60 tension 12^a has a thread to receive a knurled nut 22^b, whereby it may be drawn tautly for firm connection of the magazine to the platen frame, or released for convenient re- 65 moval thereof.

It will be understood that the weight of the magazine and its associated parts, is carried by one of the end members of the 65 platen frame, the extension 12^a fitting there-

on, and having depending flanges 12^c to secure it in position.

The extension 12^a has an upstanding arm 12^d, to which is connected, at 12^e, a friction wheel 24, which may have a corrugated 70 band of rubber 24^a about its periphery as frictional surfacing, to be in contacting relation with the peripheral surface of platen 1, and to derive rotating movement from said platen. The movement thus received 75 by wheel 24 is communicated thereby, to a friction wheel 25, which may be similarly equipped, said wheel 25, being mounted on shaft 15, serving to drive said shaft and the rolls 24 carried thereby. 80

The feeding operation of the paper sheets to the platen will be well understood from the foregoing description. The surface speeds of the rolls 14 and the platen may be equal, to synchronize their action. 85 Should the degree of frictional contact between wheel 24 and the platen require variation, this may be accomplished by tightening or loosening the nut 22^b, when a slight fall or rise is obtainable, because an elastic 90 packing 26 is interposed between the extension 12^a and the platen frame on which it is supported.

A bail or cam 27, having bent arms 27^a at its ends, is pivoted by right angular ex- 95 tensions of those bent arms, in the opposite side wings 12 of the magazine, said bail lying across the front of the paper sheets 10, to normally serve as a front guard there- 100 for. Said bail 27 has a handle 27^b at one end, and by turning the handle, the bail may be rocked to the position shown in Fig. 3; in which position said bail cams or applies pressure against the paper sheets, moving their lower edges back over the base 13, 105 and removing their forward surface from contact with the friction rolls 14, the device thus becoming inoperative.

It will be noted that no other fixed connections are employed in attaching the 110 magazine apparatus to a typewriting ma- 115 chine, and the means for removably securing said apparatus to the carriage are of the simplest character possible. Also, it should be noted that the magazine frame work, including the mounts and supports for the operative parts, may be composed of sheet metal, and, as illustrated in the example in the drawings, may be stamped or formed out of a single sheet, thereby making for 120 economy in construction, besides giving the qualities of strength and lightness.

Variations may be resorted to within the scope of the invention, and portions of the improvements may be used without others. 125

Having thus described my invention, I claim:

1. In a typewriting machine, the combination of a traveling carriage; a revoluble platen mounted in said carriage; pressure 130

- rolls co-acting with said platen; a paper table for guiding work-pieces between said pressure rolls and said platen, said table having a beading along its upper edge; a sheet magazine located above said paper table; means for consecutively feeding sheets from said magazine to said platen; and retaining means engaging said beading to hold said magazine in position.
- 10 2. In a typewriting machine, the combination of a traveling carriage; a revoluble platen mounted in said carriage; pressure rolls co-acting with said platen; a paper table for guiding work-pieces between said pressure rolls and said platen, said table having a beading along its upper edge; a sheet magazine located above said paper table; means for consecutively feeding sheets from said magazine to said platen; retaining means engaging said beading at the rear of said magazine; and a support for the front of said magazine, said retaining means and said support serving to hold said magazine in position.
- 15 3. In a typewriting machine, the combination of a traveling carriage, a revoluble platen carried thereon, pressure rolls co-acting with said platen, a paper table for guiding work-sheets between said pressure rolls and said platen, a sheet magazine supported at its rear on the upper edge of said paper table, a foot supporting said paper table at its front, and means interlocking with the paper table at the rear of the magazine, to prevent the latter from sliding toward the front or the rear of the machine, said foot being provided with means to prevent endwise movement of the said magazine along the paper table.
- 20 4. In a typewriting machine embodying a carriage provided with a paper shelf having a bead on its upper edge, the combination of a work-feeding magazine located above said shelf; a depending extension on said magazine engaging one of the end members of the carriage, to support the magazine and prevent endwise movement thereof relatively to said carriage; and retaining hooks secured to the rear portion of said magazine and engaging said bead of the magazine.
- 25 5. In a typewriting machine embodying a carriage provided with a paper shelf having a bead on its upper edge, the combination of a work-feeding magazine located above said shelf; a support on said magazine engaging said carriage, to prevent endwise movement of said magazine relatively to said carriage; retaining hooks secured to said magazine and engaging said bead; and means acting conjointly with said hooks, when so engaged, to prevent tilting of said magazine.
- 30 6. In a typewriting machine, embodying a carriage provided with a paper shelf, the combination of a work-feeding magazine located above said shelf; a depending extension on said magazine resting on one of the end members of said carriage, to support the magazine and prevent endwise movement thereof relatively to said carriage; retaining means on the rear portion of said magazine for engagement with said shelf; and a hook connection between said extension and said end member, said hook connection acting conjointly with said retaining means, when so engaged, to prevent tilting of said magazine.
- 35 7. In a typewriting machine embodying a platen frame and platen, the combination of a work-piece magazine disposed above said frame and provided with a depending extension, said extension having a horizontal portion fitting over and connected to the adjacent end member of the frame to support said magazine, and an upstanding arm on said horizontal portion; a gear rotatably mounted on said arm and in contact with said platen to be driven thereby; a horizontal shaft journaled in said magazine above and parallel with said platen; devices secured to said shaft to feed the work-pieces from said magazine; and a gear secured to said shaft and contacting with the first-named gear to be driven thereby.
- 40 8. In a work-feeding apparatus, the combination, with a magazine adapted to contain a stack of work-pieces, and means for feeding the work-pieces therefrom; of means for moving said stack of work-pieces, while in the magazine, bodily out of the range of action of said feeding means, to interrupt the feeding operation.
- 45 9. In a work-feeding apparatus, the combination, with a magazine adapted to contain a stack of work-pieces, and feeding means operative upon one side of the stack of work-pieces; of means operative upon the other side of said stack of work-pieces, while in the magazine, for moving it bodily out of the range of action of said feeding means, to interrupt the feeding operation.
- 50 10. In a work-feeding apparatus, the combination, with a magazine adapted to contain a stack of work-pieces, and means for feeding the work-pieces therefrom; of cam means for moving said stack of work-pieces bodily out of the range of action of said feeding means, to interrupt the feeding operation.
- 55 11. In a work-feeding apparatus, the combination, with a magazine adapted to contain a stack of work-pieces, and means for feeding the work-pieces therefrom; of a pivotally-mounted member for moving said stack of work-pieces bodily out of the range of action of said feeding means, to interrupt the feeding operation.
- 60 12. In a work-feeding apparatus, the combination, with a work-piece magazine, and

feeding means for the work-pieces therein; of a bail pivoted to said magazine for moving said work-pieces out of the range of action of said feeding means, to interrupt 5 the feeding operation.

13. In a work-feeding apparatus, the combination, with a work-piece magazine, and feeding means for the work-pieces therein; of a bail pivoted to said magazine 10 for moving said work-pieces out of the range of action of said feeding means, to interrupt the feeding operation, said bail having one end extended beyond said magazine and bent to form an operating handle.

14. In a work-feeding apparatus, the combination, with a magazine adapted to contain a stack of work-pieces, and means for feeding the stack of work-pieces bodily therefrom; of means normally forcing said 20 work-pieces into position to be acted upon by said feeding means; and means operative in opposition to the last-named means for forcing said stack of work-pieces bodily out of such position, to interrupt the feeding 25 operation.

15. In a work-feeding apparatus, the combination, with a magazine adapted to contain a stack of work-pieces, and means for feeding the work-pieces therefrom; of a 30 spring-controlled follower normally forcing said stack of work-pieces bodily into position to be acted upon by said feeding means; and means operative in opposition to the action of said follower for forcing said stack 35 of work-pieces bodily out of such position, to interrupt the feeding operation.

16. In a work-feeding apparatus, the combination, with a magazine adapted to contain a stack of work-pieces, and frictional 40 work-feeding rolls therein; of a manually-operated cam device for forcing said stack of work-pieces bodily away from said rolls, to interrupt the feeding operation.

17. In a work-feeding apparatus, the combination, with a magazine adapted to contain a stack of work-pieces, and frictional work-feeding rolls therein; of a manually-operated bail pivoted to said magazine for 45 forcing said stack of work-pieces bodily

away from said rolls, to interrupt the feeding operation.

18. In a work-feeding apparatus, the combination, with a magazine adapted to contain a vertical stack of work-pieces, said magazine having an open front, and a movable stack-supporting frame located at the back of the magazine; of work-feeding means projecting into said magazine; spring means for forcing said frame and stack forward, to move the foremost work-piece into 55 position to be acted upon by said feeding means; and a movable member extending across the front of said magazine for forcing said stack and frame rearward in opposition to said spring means, to move the stack out 60 of the range of action of said feeding means and thereby interrupt the feeding operation.

19. In a work-feeding apparatus, the combination, with a magazine adapted to contain a vertical stack of work-pieces, said 70 magazine having an open front, and a movable stack-supporting frame located at the back of the magazine; of work-feeding rolls projecting into said magazine; spring means for forcing said frame and stack forward, 75 to move the foremost work-piece into position to be acted upon by said feeding rolls; and a movable member extending across the front of said magazine for forcing said stack and frame rearward in opposition to said 80 spring means, to move the stack out of the range of action of said feeding rolls and thereby interrupt the feeding operation.

20. In a work-feeding apparatus, the combination, with a magazine adapted to contain a stack of work-pieces, and means for feeding the work-pieces therefrom; of means normally forcing said stack of work-pieces bodily into position to be acted upon by said feeding means; and cam means 90 operative in opposition to the last-named means for forcing said stack of work-pieces bodily out of such position, to interrupt the feeding operation.

JOHN H. SHECKLER.
